(57) **CLAIM**

The ornamental design for boat seating as shown and described.

DESCRIPTION

FIG. 1 is a front perspective view of boat seating according to our new and ornamental design.

FIG. 2 is a rear perspective view thereof.

FIG. 3 is a side view thereof.

FIG. 4 is an opposite side view thereof.

FIG. 5 is a front view thereof.

FIG. 6 is a rear view thereof.

FIG. 7 is a top view thereof.

FIG. 8 is a front perspective view thereof, having a seat cushion removed; and,

FIG. 9 is a top view thereof, having the seat cushion removed.

The broken lines in the drawings illustrate portions of the boat seating that are not part of the claimed design.

1 Claim, 9 Drawing Sheets
